UNITED STATES PATENT OFFICE.

CHRISTIAN RUCHTI, OF KINSMAN, OHIO.

CAN.

No. 909,230.

Specification of Letters Patent.

Patented Jan. 12, 1909.

Application filed September 23, 1908. Serial No. 454,288.

To all whom it may concern:

Be it known that I, CHRISTIAN RUCHTI, a citizen of the United States, residing at Kinsman, in the county of Trumbull and State of Ohio, have invented a new and useful Can, of which the following is a specification.

This invention relates to cans for shipping milk and the like, and it is more especially an improvement upon the construction described and claimed in an application for United States Patent filed by me on July 22nd, 1908, Serial No. 444,848.

The principal object of the invention is to provide a can of this character with a closure or cap so shaped as to receive and hold any water or dirt which may be dropped upon the can and which otherwise might work around and past the edges of the closure and into the can.

Another object of the invention is to improve the construction of closures such as used in connection with cans of this character and to provide simple and efficient means for retaining the cap or closure in position within the can.

Another object is to provide a closure which cannot be removed except by destroying it or so mutilating it as to render it unfit for further use.

With these and other objects in view the invention consists of certain novel details of construction and combinations of parts hereinafter more fully described and pointed out in the claims.

In the accompanying drawings the preferred form of the invention has been shown.

In said drawings:— Figure 1 is a vertical section through the neck portion of a can having the present improvements applied thereto. Fig. 2 is a detail view of the cap or closure shown in Fig. 1. Fig. 3 is a view similar to Fig. 1, but showing a modified form of the cap. Fig. 4 is a detail view of the cap shown in section in Fig. 3.

Referring to the figures by characters of reference 1 designates a milk can or other receptacle having a neck 2 in which is arranged an annular supporting bead 3. A groove 4 is formed in the neck directly above the bead 3 and constitutes a seat for an ordinary disk cap or stopper, such as usually employed on a smaller scale in milk bottles and the like. The neck 2 gradually increases in diameter from the grooved por-

tion 4 towards the outer end of the neck, as indicated at 5, there being a flared outer end to the neck as at 6. An interior rib or bead 7 is formed within the tapered intermediate portion 5 of the neck and constitutes a locking device as hereinafter set forth. The closure used in connection with the can consists of a circular disk 8 having an annular flange 9 upstanding therefrom and inclined thereto, the upper or free edge portion of the flange being extended laterally or flared as shown at 10. An annular groove 11 is formed within the flange 9 between the upper and lower edges thereof and is so proportioned as to constitute the seat of the bead 7 hereinbefore referred to.

When it is desired to seal the can shown in Fig. 1 the closure which has been illustrated in detail in Fig. 2 is placed in the neck 2 so that the flange 9 thereof will come into contact with the tapered intermediate portion 5 of the neck and said closure is forced downward a sufficient distance to permit the bead 7 to spring into the annular groove 11, the bead and groove co-operating to hold the closure in position and prevent it from being accidentally displaced. When the closure is thus located the flared portion 10 thereof bears on the flared portion of the neck. When the closure has been placed in this position it becomes difficult to remove it, and, in order to facilitate this removal, an eye 12 is preferably secured to the flange 9 where it can be conveniently engaged by a suitable tool. By exerting sufficient force upon the eye the closure can be sprung outwardly out of engagement with the retaining bead 7 and the contents of the can then removed.

With this construction it will of course be seen that the closure, as well as the can, can be used over again. When it is desired to use, in connection with the can, a closure which can only be used once, a cap or closure such as shown in detail in Fig. 4 may be utilized. This closure consists of a disk 13 having an annular flange 14 which is inclined relative to the disk and which is so proportioned that when the closure is forced into the tapered intermediate portion 5 of the can neck, said flange will assume a position between the beads 3 and 7. After the closure has been thus positioned it becomes obviously impossible to remove it from the neck of the can, because no means are provided whereby the free edge

of flange 14 can be drawn inwardly out of engagement with the rib 7. In order to open the can after this form of closure has been applied, it becomes necessary to press 5 downward on the middle portion of disk 7 with sufficient force to buckle the flange 14 so that it will spring out of engagement with the rib 7. This however will so mutilate the closure as to prevent it from being 10 re-used without detection.

It will be noted that when a closure such as shown in Figs. 1 and 3 is applied it becomes practically impossible for any water to drain past the closure and into the can. 15 This has heretofore been a source of annoyance, because when cans have been left exposed to rain, etc., or placed where drippings from cars, platforms and the like might fall upon them, the liquid often 20 drains into the cans and renders the contents thereof unfit for use. With the present form of closure however any liquid thus deposited on the cans will be received and held by the closures. This is especially desirable 25 where small quantities of objectionable liquid drip upon the cans.

As shown in Figs. 1 and 3, the necks of the cans are preferably reinforced by means of a finishing sleeve 15 which extends 30 around the grooved and beaded portion of the neck.

What is claimed is:—

1. The combination with a milk can or the like having a neck, and supporting and 35 retaining beads within the neck; of a closure comprising a disk and an annular flange thereon disposed to project between the beads.

2. The combination with a milk can or 40 the like having a neck and supporting and retaining beads within the neck; of a receptacle within the neck and engaging the retaining beads, said receptacle constituting a closure for the neck.

45 3. The combination with a milk can or

the like having a neck and upper and lower retaining and supporting beads within the neck; of a closure engaging said beads and comprising a disk, and an inclined annular flange thereon.

4. The combination with a milk can or the like having a neck, and upper and lower retaining and supporting beads within the neck; of a receptacle insertible into the neck and into engagement with said beads and 55 means within the receptacle for facilitating the withdrawal thereof from the neck.

5. The combination with a milk can or the like having a neck and upper and lower retaining and supporting beads within the neck, that portion of the neck between the beads being tapered; of a closure insertible into the neck and into engagement with the beads, said closure comprising a disk and an inclined annular flange, the tapered portion 60 of the neck constituting a seat for the flange, said flange being disposed to engage and to be retained by the retaining rib, said closure constituting a receptacle.

6. The combination with a milk can or the like having a neck and upper and lower retaining and supporting beads within the neck, that portion of the neck between the beads being tapered; of a closure insertible into the neck and into engagement with the 65 beads, said closure comprising a disk and an inclined annular flange, the tapered portion of the neck constituting a seat for the flange, said flange being disposed to engage and to be retained by the retaining rib, said closure constituting a receptacle, and means 70 within the closure for facilitating the withdrawal thereof from the neck.

In testimony that I claim the foregoing as my own, I have hereto affixed my signature in the presence of two witnesses. 75

CHRISTIAN RUCHTI.
